UNITED STATES PATENT OFFICE.

McDUFFIE BRADFORD, OF NOCONA, TEXAS.

SYRUP-PITCHER.

No. 823,663.

Specification of Letters Patent.

Patented June 19, 1906.

Application filed November 6, 1905. Serial No. 286,083.

To all whom it may concern:

Be it known that I, McDUFFIE BRADFORD, a citizen of the United States, residing at Nocona, in the county of Montague and State of Texas, have invented a new and useful Syrup-Pitcher, of which the following is a specification.

This invention relates to improvements in attachments to syrup-pitchers, and has for its object to provide a simply-constructed and automatically-operating device whereby all tendency of the syrup to drip over the edge of the rim or pouring-spout is obviated and to arrange the device so that it can be readily removed for cleaning or for other purposes.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

Figure 1 is a perspective view of the improved device with the lid open. Fig. 2 is a sectional view with the lid closed. Fig. 3 is a perspective view of the movable lip and its bail detached. Fig. 4 is a perspective view of the coupling-bar detached.

The improved device may be readily adapted to any of the various forms of the neck and closure portions of syrup-pitchers by making slight and immaterial changes in some of the parts; but for the purpose of illustration the device is shown applied to an approved neck structure in which the band portion 10 for encircling the throat of the pitcher, the outwardly-curving rim 11, the inwardly-extending flange 12, the lid or closure 13, and the spring-hinge 14, connecting the lid to the rim, are of the usual form.

Extending from the flange 12 at opposite sides are perforated ears 15, and disposed between these ears is a lip member 16, of resilient sheet metal and provided with oppositely-extending pintles 17, engaging the ears 15 and upon which the lip swings. The lip member corresponds in shape to the pouring-lips usually employed upon syrup-pitchers, and when in one of its positions or when the

lid 13 is open the lip will bear upon the flange 12 and serve the purpose of a pouring-spout in the ordinary manner, as represented in Fig. 1. Rigidly attached to the lip member 16 and extending rearwardly of the same is a bail 18, having spaced collars 19 centrally disposed thereon. The pintles 17 and the bail 18 are in one piece of wire, the pintles being formed by bending the ends of the wire laterally in opposite directions, extending them through the ends of the lip member 16, as shown in Fig. 3. Extending from the interior of the lid 13 is a loop or eye 20, and detachably engaging this eye by a hook 21 at one end is a rod 22, the other end of the rod having an eye 23, encircling the bail 18 between the ears 19.

The rod 21 is so formed as to length that when the lid 13 is in open position, as in Fig. 1, the bail will be drawn upwardly to seat the lip member 16 upon the flange 12 in position to serve as a pouring-spout, as in Fig. 1, and then when the lid is closed the rod will depress the bail and rock the lip upon its pintles 17 and elevate the forward edge of the lip from the flange, as in Fig. 1, to permit the syrup which may have lodged between the lip and rim 11 to flow back into the pitcher, and thus avoid overflow when the lid is again raised for the next pouring action.

The lip 16 and bail 18 being of resilient material, and the hook 21 being of the open form, the lip-bail and rod may be easily detached by simply compressing the lip and its bail until the pintles 17 are free from the ears 15 and then unhooking the rod from the loop-eye 20. By this means the whole attachments may be quickly removed when required for cleansing or when the pitcher is to be cleansed or for other purposes.

Having thus described the invention, what is claimed is—

1. In a syrup-pitcher a neck member having an inwardly-extending flange, a lid hinged to said neck and provided with an eye depending from its interior, spaced apertured ears extending from said flange, a resilient lip disposed between said ears and bearing upon said flange and with laterally-extending pintles movably engaging said ears a bail connected to said lip, and an arm movably engaging said bail at one end and with an open hook at the other end for detachably engaging the eye within said lid.
2. In a syrup-pitcher, a neck member hav-

ing an inwardly-extending flange, a lid hinged to said neck and provided with an eye-loop, spaced ears transversely apertured and extending from said flange, a resilient lip disposed between said ears and bearing upon said flange, a resilient bail having outturned ends extending through said lip and forming pintles for passing through said ears, and an arm movably engaging said bail at one end and terminating in a hook at the other end

for detachable engagement with loop-eye of said lid.

In testimony that I claim the foregoing as my own I have hereto affixed my signature in the presence of two witnesses.

McDUFFIE BRADFORD.
